ATTORNEY

UNITED STATES PATENT OFFICE.

CLAUDE J. OLES, OF UNADILLA, NEW YORK.

SINK TRAY.

Application filed August 15, 1924. Serial No. 732,263.

To all whom it may concern:

Be it known that I, CLAUDE J. OLES, a citizen of the United States, residing at Unadilla, in the county of Otsego and State of New York, have invented new and useful Improvements in Sink Trays, of which the following is a specification.

This invention relates to sink trays.

The object is to provide a tray or rack for use in sinks to support dishes, pots or pans above the bottom of the sink so as to avoid breaking the dishes or damaging the sink during the process of washing the articles mentioned.

Another object is to provide a tray of this character which may be easily and cheaply manufactured and sold at a very low cost to be placed into a sink for supporting dishes, etc., in a manner to permit the same to drain, the said tray being constructed of a minimum number of parts so formed and assembled as to obviate the necessity for using fasteners of any kind, and at the same time prevent distortion of the tray while in use.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claim.

In the drawing, in which similar reference characters designate corresponding parts throughout the several figures:—

Figure 1 is a perspective view of the improved tray;

Figure 2 is an enlarged transverse sectional view of the same;

Figure 3 is a further enlarged detail of one end of one of the cross bars of the tray.

Figure 4 is a detail view, still further enlarged and taken at right angles to Figure 3;

Figures 5 and 6 are views similar to Figures 3 and 4 respectively and showing a slight modification.

Referring to the drawing there is shown

a sink tray comprising a pair of spaced, longitudinally disposed sills 1, preferably formed of suitable wood, such as maple, and arranged parallel to each other a distance apart to be placed within an ordinary sink of average dimensions and to rest upon the bottom thereof.

The wooden sills 1 have the intermediate portions of their undersides cut out, as indicated at 2, thus providing, at each terminal thereof, a foot 3 which is adapted to rest upon the bottom of the said sink and, at the same time, the cut-out portion 2 permits water in the sink to freely pass through from side to side.

The upper sides 4 of the sills 1 are each rounded, as clearly shown in Figures 1 and 2 of the drawing, to cause water to pass off and, in the construction of the device, a series of sockets or holes 5 are formed in spaced longitudinal alinement along the center line of the rounded top side, said holes being equidistant and extending only a slight distance into the said sills, which are somewhat higher than wide to provide a stiff, strong structure.

Cross bars 6 formed of stiff round wire or rod material are adapted to connect the sills together and hold the same in rigid, spaced relation to each other, the length of said cross bars being such as to permit the sills to enter between the side walls of the sink.

The terminal portions or ends of each cross bar 6 are bent at right angles thereto, as indicated at 7, and the major portion of each bent terminal is tapered to provide penetrating points 8 which are adapted to be driven or forced into the aforesaid holes 5 which latter, as originally formed, are somewhat smaller in diameter than the diameter of the wire or rod forming the cross bars, so that, as the points are forced in, the wood is separated or spread apart to receive the same, and the frictional engagement is thus enhanced, without the danger of splitting the wooden sills, were the said points driven thereinto without the provision of the said holes.

In order to prevent the relative, longitudinal movement of the sills, which would be possible were the said points 8 allowed to partake of any turning movement in their respective sockets, the said points are preferably provided with a plurality of longitudinally disposed corners or ridges 9, which

may be formed by hammering the points into a four-sided, tapering point, or the same may have any other desired number of such ridges to engage in the wood and prevent the terminals of the cross bars from turning in the sills. In Figures 5 and 6 the points are provided with a plurality of longitudinally disposed concavities 10 thus providing intervening ridges for the above purpose.

From the foregoing it will be seen that an extremely simple and cheaply manufactured tray or rack has been provided which may be placed between the side walls of a sink and upon the bottom thereof without danger of damaging the said sink; that by reason of the particular manner of joining the cross bars to the side sills, the necessity for special fastenings is obviated, and that the engagement of the terminals of the cross bars with the sills prevents the latter from relative, longitudinal movement so that the tray may not become distorted during usage; that the dishes, pots, and pans placed upon

the tray may freely drain while supported above the sink in a manner to avoid contact with the latter, and that the said device may be easily kept in a clean and sanitary condition.

What is claimed is:—

A sink tray comprising a pair of spaced, parallel, wooden sills, each sill having its upper face formed with sockets extending downwardly partway into the sill, and also having depending foot portions at the terminals thereof, and a plurality of spaced metallic cross bars connecting the sills, each cross bar having its terminals bent downwardly and pointed to be forced into said sockets, the latter being of less diameter than said pointed terminals for the purpose set forth, and each pointed terminal having longitudinal ridges to prevent turning in their respective sockets.

In testimony, that I claim the foregoing as my own, I have hereto affixed my signature.

CLAUDE J. OLES
